UNITED STATES PATENT OFFICE.

CHARLES K. PICKLES, OF ST. LOUIS, MISSOURI, ASSIGNOR TO FAIRBANKS, MORSE & COMPANY, OF CHICAGO, ILLINOIS, A CORPORATION OF ILLINOIS.

FLUID-PRESSURE IMPACT-TOOL.

SPECIFICATION forming part of Letters Patent No. 794,738, dated July 18, 1905.

Application filed May 31, 1901. Serial No. 62,582.

To all whom it may concern:

Be it known that I, CHARLES K. PICKLES, a citizen of the United States of America, residing in the city of St. Louis, State of Missouri, have invented certain new and useful Improvements 5 in Fluid-Pressure Impact-Tools, of which the following, taken in connection with the accompanying drawings, is a specification.

My invention has reference to the provision 10 of improvements in the type of mechanism specified, in which, the piston is driven backward and forward by pressure admitted alternately at its opposite ends through control exercised by a suitable valve placed in a valve 15 chamber adjacent to the piston chamber and connected therewith by suitable ports and passages, the valve being governed in its movements by suitable ports controlled by the piston.

20 In order to make my invention clear I have illustrated it in preferred form in the accompanying drawings, in which, Figure 1 is a side sectional view of a tool embodying my improvements, Figure 2 is a sectional view of the 25 impact piston, Fig. 3 is a side elevation of the controlling valve, Fig. 4 is a side elevation of the controlling valve bushing, Fig. 5 is a vertical section showing the parts in a different position from that shown in Fig. 1, Fig. 6, is

30 a section taken on the line 6—6 of Fig. 5, Fig. 7 is a section taken on the line 7—7 of Fig. 5, Fig. 8 is a section taken on the line 8—8 of Fig. 5, all of the last mentioned three figures being designed particularly to show the different 35 connections and port openings involved in the operation of the device.

In constructing a tool in accordance with my invention I provide, first, a suitable cylinder 9, carrying in its forward end a tool socket 40 or bushing 10, which may be of any preferred construction, so formed as to permit the tool to be held against rotation or to permit the tool to rotate within the bushing as may be desired. At the end of the cylinder 9, opposite the said tool socket, is connected a handle, by means of a handle hub 11 having screw threaded engagements with the exterior of the cylinder 9, and locked in position, after it is

screwed on, by means of a suitable locking pin 22. The handle mechanism itself may be 50 of any preferred construction, but I have for convenience shown a well known form in which the throttle is located in the lower portion, and the duct through which the pressure reaches the tool passes through the lower 55 connecting neck between the grasping portion and the hub of the handle. The throttle valve is controlled by means of a trigger lever of the usual type.

Within the cylinder I provide a piston bushing 12 open at its forward end and closed at its rear end by means of a piston chamber cap 14 held in place by a spring in the form of a disk 15 pressing against the rear of the cap and held by means of a portion of the handle 60 hub whereby the closure cap is not only held tightly against the piston bushing but a slight amount of spring is obtained which tends to take up such wear as may occur in the threaded connection between the handle hub and the 65 cylinder on account of the constant vibration and jolt to which the tools are subject in use. The cap 14 is located within a chamber 14° formed in the handle hub so as to permit the 70 air pressure to act against the rear side of the 75 cap as well as the front side and keep the same in equilibrium.

Within the piston bushing is arranged a piston 13 the same being provided with two 80 annular grooves or passages 13^b and 13^c the latter connected with the forward end of the piston by longitudinal channels 13^d and the former with the rear end of the piston by means of a port or opening 13^a constructed to be closed by means of a ball check valve 21 85 for a purpose which will be hereinafter pointed out.

Within the lower part of the handle hub is inserted a valve bushing 17 adapted to receive the controlling valve 16 and closed at its lower 90 end by means of a chamber cap 18, which is provided with a tubular extension 19 that projects through the valve. The valve bushing is provided with an inlet port 17^a and with three exhaust ports the two marked 11^b being 95 ports for allowing the pressure to exhaust

when the piston is being returned or reset after an impact stroke and the one marked 11^a for permitting the exhaust of the pressure in advance of the piston as it is making its impact stroke. The last mentioned port 11^a is connected with the forward end of the piston chamber by means of an annular passage 12^c formed in the exterior of the piston chamber bushing and three longitudinal passages one 10 on each side and one on the top of the piston bushing which extends to the forward end thereof.

The valve 16 is what is known as a differential valve having an enlarged end 20, which 15 works within an enlargement of the valve chamber the lower end being connected by means of a passage 12^a formed longitudinally in the lower side of the piston bushing 12, as clearly shown in the drawings. The tubular 20 extension 19 is open at the upper end to the inlet passage so that it is constantly supplied with fluid pressure and has near its lower end a small port 19^a controlled by the valve, which when the valve is in upper position permits 25 the air to flow into the passage 12^a for resetting or returning the piston after it has made an impact stroke and also for the purpose of holding the valve in its upper position during the return or resetting stroke of the piston.

30 The operation of my invention is as follows: Air having been admitted by the opening of the throttle valve the fluid pressure acting on small area moves the valve to the position shown in Fig. 5, whence it passes through the 35 impact ports 17^a and the radial ports 12^e into the rear end of the piston chamber forcing the piston forward to deliver an impact blow, the piston at the time of striking the tool being in the position shown in Fig. 5 at which time 40 air then enters through the check valve passage 13^a and the annular port 13^b and passing thence through the valve change port 12^b in the piston bushing acts backwardly into the enlarged end of the piston chamber and 45 against the end 20 of the valve to force the valve back to the position shown in Fig. 1. This opens the resetting port 19^a permitting fluid pressure to enter to hold the valve in this position, and, at the same time passes to 50 the forward end of the piston chamber to move the piston back, the rear end of the piston chamber being meanwhile in communication with the atmosphere through the ports and passages 12^d, 12^e, and 11^b, respectively.

55 As the piston continues its resetting or backward stroke it finally passes the radial ports 12^e and then cushions upon the air confined in the rear of the piston chamber, the pressure therein being gradually permitted to escape 60 through the small passage 12^g which latter serves the purpose also of admitting the pressure to produce the initial movement of the piston at the beginning of its impact stroke. As the piston reaches the rear end of its 65 stroke it opens communication between the

fluid pressure in its forward piston chamber and the atmosphere through the passage 13^d and the annular channel 13^e whereby the pressure on the large end of the valve is removed and the constant pressure on the small end thereof causes a change in the valve position shifting it again to the position shown in Fig. 5.

70 My invention is applicable to either a long or a short stroke hammer, it being useful for a long stroke hammer without the addition of any auxiliary or secondary valve, the valve mechanism being peculiarly well adapted for such purpose owing to its location at the side of the piston chamber along which it extends longitudinally thus appreciably shortening the length of ports necessary to establish communication between the valve chamber and the forward end of the piston chamber. The use of the check valve carried by the piston 75 is also of peculiar utility in a long stroke hammer.

80 Having thus described my invention, what I claim as new, and desire to secure by Letters Patent, is—

90 1. The combination with a fluid-pressure actuated impact tool having a cylinder, an impact piston, and a piston chamber, of a valve chamber, ports and passages connecting said piston chamber and said valve chamber, a valve operating in said valve chamber and controlling said ports and passages, and a tubular extension within said valve, substantially as described.

95 2. The combination with a fluid-pressure actuated impact tool having a cylinder, an impact piston and a piston chamber, of a valve chamber, ports and passages connecting said piston chamber and said valve chamber, a valve operating in said valve chamber and controlling said ports and passages, and a tubular extension within said valve, said tubular extension being open at one end to constant pressure and provided at the other end with a resetting port, substantially as described.

100 3. A valve mechanism for fluid-pressure actuated impact tools comprising a valve having differential pressure areas, a chamber within which said valve operates, and a tubular extension within said valve, said tubular extension being provided with a resetting port controlled by the valve, substantially as described.

105 4. The combination with a pneumatic tool having a cylinder, and impact piston, a piston chamber, and suitable controlling valve mechanism, of a port in said piston for changing the position of said valve, said valve change port being controlled by a check valve, substantially as described.

110 5. A fluid-pressure impact tool comprising a cylinder, an impact piston, a valve, ports and passages and means carried in said piston whereby a reversal of the valve may be effected, by fluid pressure from the piston chamber.

6. A fluid-pressure impact tool comprising a cylinder, having ports, and passages, and impact piston and means carried in said piston whereby a communication may be established 5 between the forward and rear piston chamber to effect a retraction of the piston, substantially as described.
7. A fluid-pressure impact tool comprising a cylinder, having ports and passages, and 10 means carried in said piston whereby a communication may be established between the forward piston chamber and the atmosphere to effect a release of motive fluid, substantially as described.
- 15 8. A fluid-pressure impact tool comprising a cylinder, having ports and passages in communication with a valve, and a piston having passages adapted to open communication into one side of said valve to effect a movement in 20 one direction, by the admission of motive fluid from the rear piston chamber, substantially as described.
9. A fluid pressure impact tool comprising a cylinder, having ports and passages, a piston 25 adapted to have movement therein, and having passages whereby, motive fluid is admitted from the rear piston chamber, to move the valve in one direction, and means carried by said piston whereby, motive fluid is exhausted 30 from the forward piston chamber, to effect a movement of the valve in the opposite direction, substantially as described.
10. A fluid pressure impact tool comprising a cylinder, having ports and passages, a piston 35 adapted to travel therein a greater distance than its own length, and a valve, adapted to control the admission of motive fluid through itself to both ends of said cylinder to effect a movement of the piston, and means carried by the piston for effecting a reversal of the 40 valve.
11. The combination with a pneumatic tool having a cylinder, an impact piston, a piston chamber, and suitable controlling valve mechanism, of a valve port for changing the position of said controlling valve mechanism, said valve change port being provided with a check valve, substantially as described. 45
12. The combination with a pneumatic tool having a cylinder, an impact piston, a piston 50 chamber, and suitable controlling valve mechanism comprising a piston having large and small area, of a valve port for changing the position of said controlling valve mechanism, said valve change port being provided with 55 means whereby to prevent reflux of motive fluid from the chamber at one side of the large area of the valve, back into the piston chamber, substantially as described.
13. A fluid pressure impact tool comprising 60 a cylinder having passages and ports, a separate valve with ports connected to said passages, a piston traveling in said cylinder, and means allowing fluid pressure behind the piston to escape through said passages to shift 65 the valve and means in the piston preventing return of pressure through the passages to said rear of the piston.

CHARLES K. PICKLES.
